UNITED STATES PATENT OFFICE.

RAYMOND W. COLLINS, OF DETROIT, MICHIGAN, ASSIGNOR TO MOTOR PRODUCTS CORPORATION, OF DETROIT, MICHIGAN, A CORPORATION OF NEW YORK.

WIND-SHIELD CONSTRUCTION.

1,295,697.

Specification of Letters Patent. Patented Feb. 25, 1919.

Application filed July 5, 1917. Serial No. 176,559.

To all whom it may concern:

Be it known that I, RAYMOND W. COLLINS, a citizen of the United States of America, residing at Detroit, in the county of Wayne and State of Michigan, have invented certain new and useful improvements in Wind-Shield Construction, of which the following is a specification, reference being had therein to the accompanying drawings.

This invention relates to windshields and refers more particularly to windshields of the ventilating type such as are employed on automobiles or the like.

15 In windshields of the ventilating type it is common to provide the ventilating section with a recess along its lower edge adapted to fit tightly over a gate formed on the lower rail. In such constructions it is necessary to adjust the ventilating section vertically out of engagement with the gate prior to swinging the section about its pivot, and heretofore in disengaging the ventilating section from the gate it has been usual 20 to lift the section by hand before swinging it to its ventilating position.

The present invention contemplates an improved mechanical means by which the ventilating section can be raised and disengaged from the gate, this lifting mechanism being preferably combined with the pivot mechanism and with the locking mechanism for the pivot. The invention further resides in such features of construction and 25 arrangements and combinations of parts as will more fully hereinafter appear.

In the drawings:

Figure 1 is a fragmentary rear elevational view of a windshield embodying my invention;

40 Fig. 2 is an elevational view of one of the standards.

Fig. 3 is a vertical section on the line 3-3 of Fig. 1;

45 Fig. 4 is an enlarged vertical sectional view of the lifting mechanism.

Describing in detail the particular construction shown in the drawings, A designates one of the uprights or standards which carry the windshield sections, such as the main windshield section B and the lower or ventilating section C, these sections overlapping as indicated at D. The standards are preferably formed with a split bearing 50 D' for receiving the pivot E of the upper

or main section and with a split bearing F for receiving the pivot member G of the lower or ventilating section. To lock the sections in various positions of adjustment, these split bearings are adapted to be tightly contracted around the pivots into frictional locking engagement therewith. For this purpose the split bearing D' is provided with a bolt H which extends through the lugs I and I' on the split bearing, the bolt 60 at its upper end having a head H' and at its lower end having pivoted thereto at J' a cam J operated by a handle J².

When this handle J² is turned downward the enlarged portion J³ of the cam J rides 70 against the abutment I² and draws the head H' of the bolt downward, thus forcing the lugs I and I' toward each other and tightly contracting the split bearing D' about the pivot E. When it is desired to swing the 75 section to a different position the handle J² is moved upward, thus withdrawing the enlarged cam portion J³ out of engagement with the abutment I² and permitting the lugs I and I' to spring away from each 80 other back to their normal position where the split bearing D' releases its frictional engagement with the pivot E. The windshield section B can then be sprung to the desired position and again locked in its new 85 position by turning down the handle J².

The split bearing F for the pivot G of the lower or ventilating section C is also provided with a similar locking arrangement comprising the lugs L and L' and the bolt 90 M extending through the lugs and provided with a head M', pivoted cam N which has an enlarged cam portion N³, operating handle N² by means of which the enlarged portion of the cam is rocked into and out of engagement with the abutment M². However as the frame O of the lower section C has a recess O' adapted to tightly receive the gate Q, it is necessary to move this ventilating section C vertically before swinging it 100 about its pivot to the position shown in Fig. 2.

The present invention particularly contemplates mechanical means for lifting the ventilating section prior to swinging it about its pivot and in the present construction this lifting mechanism is combined with the pivot and pivot locking mechanism. In detail the lifting mechanism comprises a bushing R which is split at R' and revolvably 110

mounted within the split bearing F. The bushing has an eccentrically arranged circular recess adapted to receive the pivot G of the ventilating section C. The split eccentric bushing R is preferably provided with an operating handle R² by means of which its enlarged portion R³ can be rocked beneath the pivot F. The operation of the adjustment of the lower section C from its closed position to its ventilating position is as follows: The handle R² is rocked downward to the position shown in Fig. 2 so as to release the tension on the lugs L and L' and thus release their frictional engagement with the eccentric bushing R and the pivot G. The handle R² is then rocked upward, bringing the enlarged portion R³ of the eccentric bushing beneath the pivot G as shown in Fig. 4. This will raise the section C sufficiently to disengage its recessed portion O' from the gate Q, after which the section can be sprung outward to the desired position and the parts again locked by forcing the handle N² upward until the enlarged cam portion N³ forces the lugs L and L' together and frictionally locks the parts in their adjusted position. In returning the ventilating section to its closed position, that is, to engage said section with the gate Q, the locking mechanism is first released by pulling the handle N² downward and then after the windshield section C has been returned to its closed position, the handle R² is drawn downward, moving the enlarged portion R³ of the cam R to a position above the pivot G. This positively forces the recessed lower edge of the frame O downward tightly over the gate Q.

Thus by the addition of a single member I have provided means for positively lifting and returning the ventilating section into

and out of engagement with the gate Q and have also utilized the locking means for the pivot as a locking means for the lifting mechanism. Various changes in the details of construction can, however, be made within the scope of my invention. 45

What I claim as my invention is:—

1. The combination with a windshield standard, of a windshield section having a pivot mounted in said standard, an eccentric bushing surrounding said pivot and means for rotating said bushing to lift said pivot and section, said standard having a split bearing and means for contracting said bearing around said split bushing for frictionally locking the windshield section in different positions of adjustment. 50

2. The combination with a windshield section having a pivot about which it can be moved, a gate member having interlocking engagement with the lower edge of the windshield section, an eccentric split bushing surrounding said pivot and means for rocking said bushing to one position of adjustment to raise said windshield section out of engagement with said gate member. 55

3. The combination with a windshield section having a pivot about which it can be moved, a gate member having interlocking engagement with the lower edge of the windshield section, an eccentric split bushing surrounding said pivot, means for rocking said bushing to one position of adjustment to raise said windshield section out of engagement with said gate member, and a supporting split bearing adapted to receive said split bushing, and a cam member for contracting said split bearing to frictionally interlock said pivot and bushing. 75

In testimony whereof I affix my signature.

RAYMOND W. COLLINS. 80
